BLOCK-PRINTING MACHINE

Benjamin Franklin Herr, Lancaster, Pa., assignor to Armstrong Cork Company, Lancaster, Pa., a corporation of Pennsylvania

Application September 29, 1952, Serial No. 312,150

4 Claims. (Cl. 41—1)

This invention relates to a machine for striating wet coloring material such as paint and more particularly to an apparatus for striating wet paint or the like applied to a surface with a block-printing machine.

It is customary in the manufacture of floor and wall coverings to apply the wear coating in pattern, and flat block printing machines are customarily employed, for they are capable of applying a thick layer of relatively heavy-bodied paint. Usually the pattern is defined by the outline or shape of the block-printing surfaces, but in some instances striated or so-called marbleized effects are obtained by engaging the block-applied pattern while the paint is still wet and laterally blending the applied colors of paint to obtain the desired effect. Brushes, wire card cloth, pile fabrics, air jets, and other arrangements have been provided to obtain striated effects.

The present invention is concerned with the striation of wet paints in a novel manner and is especially useful in flat block-printing machines to effect striation of wet paints applied by the flat printing blocks of the machine.

An object of the invention is to provide a machine of the type mentioned above in which striation is effected along a direction or directions diagonally of the length of the decorated fabric.

Another object of the invention is to provide a striating unit which may be mounted in a flat block-printing machine and actuated by the conventional head-elevating mechanism provided in flat block-printing machines.

A further object of the invention is to provide a striating unit which may be lowered to bring the striating material into engagement with previously applied decorating paint or the like, moved diagonally of the length of the fabric being decorated, and then removed therefrom.

Other objects of the invention will be clear from the description of an embodiment of the invention which follows, reference being made to the accompanying drawings, in which:

Figure 1 is a diagrammatic view of a printing machine illustrating the relationship of the striating units of the present invention to the flat printing blocks of a conventional flat block-printing machine;

Figure 2 is a diagrammatic view of a piece of floor covering material illustrating one type of striated pattern obtainable with the equipment of the present invention;

Figure 3 is a view in side elevation of one side of a unit of this invention;

Figures 4 and 5 are views in side elevation, with Figure 4 partially broken away, showing parts of the head-traversing mechanism;

Figures 6 and 7 are top plan views of the head-traversing mechanism shown in side elevation in Figures 9 and 10, respectively;

Figure 8 is a sectional view taken along the line 8—8 of Figure 4;

Figures 9 and 10 are views in side elevation of a head-moving mechanism similar to that of Figures 4 and 5 but arranged to effect diagonal motion to the head in a direction opposite to that of the unit of Figures 4 and 5; and

2

Figures 11 and 12 are top plan views of the head-moving mechanism of Figures 4 and 5, respectively.

The device shown in the drawings includes a conventional printing head 2 mounted on head slide 3 (one side only of the machine is shown in Figure 3) for vertical reciprocation toward and away from a bed 4, over which is positioned a web of fabric such as felt base to be decorated, the web being arranged for intermittent movement from station to station along the machine in the usual manner. Motion is imparted to each head by head-elevating cams 5 which engage cam follower rollers 6 mounted on the head slides 3 disposed on opposite sides of the bed 4. Mounted on the printing head 2 is a block 7 having a facing 8 which may be of wire card cloth or other material suitable for striating wet printing paint.

Mechanism is provided for moving the printing head 2 and the block 7 with the striating facing material 8 in a generally diagonal direction at an angle of about 45° to the length of the fabric being printed while the striating facing is in engagement with the wet printing paint deposited on the fabric, the printing head being elevated after each striating operation to permit forward movement of the fabric to bring a fresh section thereof into position for striation; whereupon, the printing head is again lowered and the striating operation is repeated.

With certain types of designs or patterns, it is desirable to striate certain areas of the fabric in one direction at a 45° angle to the length of the fabric and other areas in the opposite direction, also at a 45° angle to the length of the fabric. This may be accomplished by arranging one printing head to move at a 45° angle in one direction and another to move at a similar angle but in the opposite direction. Mechanisms for providing both motions are shown in the drawings. Figures 3, 4, 5, 8, 11, and 12 show means for moving a printing head in one direction, and Figures 6, 7, 9, and 10 show means for moving a head in an opposite direction.

Figures 4 and 5 show the moving mechanism for opposite sides of a single printing head, and Figures 11 and 12 are top plan views of the mechanism shown in Figures 4 and 5, respectively.

Referring first to Figures 3, 4, 5, 8, and 11, mounted on the head slides 3 are printing head mounting blocks 9 which as shown in Figure 4 are supported by rectangular slide blocks 10 received within rectangular openings in the mounting blocks 9, the slide blocks 10 being connected to the head slides 3 by brackets 11 each of which receives a connecting pin 12, the pin 12 passing through the slide block 10. This arrangement provides for vertical reciprocation of the printing head 2 with the head slides 3 and permits limited movement of the head in a horizontal plane. This later movement is effected in timed relationship with the vertical reciprocation of the printing head to effect the desired movement in a horizontal plane when the printing head is lowered and the striating material 8 is in engagement with the wet paint. The head-elevating cams 5 (Figure 3) are provided with a dwell surface portion 13 which follows a path concentric with the axis of the cam shaft, and thus no movement of the follower roller 6 occurs during the interval when the dwell surface 13 engages the follower roller 6. This dwell surface is provided at the lowermost point of each cam so that the head slides 3 are in their lowermost positions, as shown in Figure 3, with the striating surface 8 in engagement with the wet paint to be acted upon during the transverse motion of the head.

A head-traversing cam 14 is secured to each head-elevating cam 5 by a pressure plate cam 15 which is provided to draw the head into lowered position with the striating surface 8 penetrating the material to be striated. The head-traversing cams 14 are positioned with respect to head-elevating cams 5 and the pressure plate cams 15

in such manner that traversing of the head 2 by cams 14 is effected during the dwell of the head in its lowered position. To effect this traversing motion of the head 2, an actuating arrangement is provided on each side of the head including a cam follower roller 16 journaled in a bracket 17 which is pinned to a vertical operating shaft 18 which is in turn journaled in bearing blocks 19 and 20 fixed to the head slide 3 for movement therewith. Pinned to operating shaft 18 is a lug 21. A connecting link 22 is pivoted to the lug 21 by a pin 23. This link is also pivoted by a pin 24 to a freely pivoted link 25 which is in turn pivoted by a pin 26 to a mounting block 27 secured to the head slide 3. A lug 28 is secured to the mounting block 9, and the freely pivoted link 25 is connected thereto by pivot pin 29. A torque spring 30 encircles shaft 18 and has one end thereof secured in bearing block 20 and the other end in an adjusting collar 31 secured to shaft 18. This spring serves to move the cam roller 16 to a position for engagement with the surface of cam 14 for transverse movement of the head by the cam and serves to effect the return movement of the head to its normal or at-rest position.

It will be noted that cam 14 has an inclining portion 32 followed by a flat or dwell portion 33 and then a reclining portion 34. These are correlated with the surface of head-elevating cam 5 and the pressure plate cam 15 to provide for movement of the inclining surface 32 of the cam 14 with respect to follower roller 16 to effect traversing of the head 2 during the dwell of the head in its lowered position through surface 13 of cam 5, and with the head held in its lowered position by pressure plate cam 15. There then follows a dwell of the transverse movement of the head 2 (the dwell portion 33 of cam 14) while the head is being elevated to withdraw the striating material from the wet paint without smearing; and then, as the head continues to be elevated, a return of the head transversely to its original position by the action of spring 30, the surface 34 of traversing cam 14 permitting a gradual return of the head to its normal position.

When the vertical operating shaft 18 is rocked by movement of the traversing cam 14, in a counterclockwise direction as viewed in Figure 3, lug 21 which is pinned to shaft 18 will move to the left, drawing link 22 in that direction. This in turn pivots link 25 about pivot 26, and motion is imparted to the head through lug 28 which is pivoted at 29 to link 25, the lug 28 being fixed to the mounting block 9 which is free to slide on slide block 10 in both longitudinal and transverse directions. It will be noted from an examination of Figure 3 that the mounting block 9 is free to move to the left, being engaged on the right by the arm of bracket 11, and that it is free to move transversely to the right as shown in Figure 4. Actually, the motion imparted is in an arc with a slight rise, about $\frac{1}{64}$ of an inch, with the motion being generally at a 45° angle to the length of the printed fabric. The distance of transverse movement may be about $\frac{5}{8}$ of an inch.

The printing heads are generally quite heavy to provide for adequate rigidity to effect good uniform contact between the striating material and the wet paint, and the paints employed are relatively thick and heavy bodied. For these reasons, it is preferred to have similar traversing mechanism on each end of the printing head, one pushing the head while the other simultaneously pulls it. Figures 5 and 12 shown an arrangement for use in cooperation with the traversing mechanism of Figures 3, 4, 5, 8, and 11. The arrangement is essentially the same, and similar parts have been similarly numbered. The linkage arrangement is different, however, to provide the proper pulling motion for cooperation with the pushing motion effected on the opposite side of the printing head. The vertical actuating shaft 18 is pinned to a lug 35 which is pivoted by pin 36 to lug 28 connected to mounting block 9.

The unit described is effective for moving the printing

head 2 of Figure 1 diagonally of the length of the printing head, across the fabric in a direction generally from right to left as shown in Figure 3. To effect striation in an opposite direction, a block similar to that of Figure 3 may be provided with the traversing mechanism arranged to move the head in a diagonal direction from left to right when viewed as in Figure 3. Such an arrangement may be essentially the same as shown in the views previously described, except that the traversing cams will be positioned so as to rotate the vertical operating shafts in a direction opposite to that of the shafts 18 of Figures 6, 7, 9, and 10.

Most of the parts shown in these views are identical with those of the head-traversing mechanism of the other views, and corresponding numbers have been applied. The essential difference lies in the disposition of the traversing cams necessary to effect rotation of the vertical operating shafts in the desired direction. Also, the units are reversed in position on the machine as will be noted by comparing Figures 4 and 5 with Figures 9 and 10 and noting that the linkage arrangement of Figure 4 will be incorporated in the unit of Figure 10 disposed on the opposite side of the machine.

The traversing cams 39 of Figures 6, 7, 9, and 10 will have the same contour as the others, but as will be seen by comparing Figures 4 and 9, for instance, the cam 14 of Figure 4 will rotate the shaft 18 in a counterclockwise direction; whereas, the cam 39 of Figure 9 will rotate its vertical actuating shaft 40 in a clockwise direction.

The striating device is preferably incorporated into a flat block-printing machine such as diagrammatically shown in Figure 1. There a web of fabric such as a felt floor or wall covering foundation 41 is fed from a roll over the bed 42 of the printing machine, and a base color and two striating colors are applied by printing blocks 43, 44, and 45, respectively. The fabric carrying the wet printing paints deposited at the stations of blocks 43-45 is intermittently moved into the station of striating block 46 and certain of the pattern elements are striated in a diagonal direction, such as the elements 47 and 48 of Figure 2. The web is then intermittently moved to the station of striating block 49, and other pattern elements are striated in a diagonal direction, as indicated at 50 and 51 in Figure 2, generally at right angles to the direction of the striations 47 and 48 of that figure, for example. This produces a striated pattern similar to a jaspe grained linoleum laid in individual blocks with diagonally directed jaspe graining.

The fabric may be delivered from the printing machine to a curing chamber as indicated in Figure 1, should the nature of the surface decoration require. Oil paints normally require a stoving period at elevated temperatures; other paints and coating materials may be air dried, fused by radiant heating, or otherwise hardened for use after striation.

I claim:

1. In a decorating machine, the combination of a head, striating means carried by the head, elevating means for raising and lowering said head to bring said striating means into position to striate material intermittently positioned therebelow and to elevate said striating means out of engagement with said material to permit movement of a fresh area to be striated into position below said striating device, and means carried by said head-elevating means for moving said striating means diagonally with respect to its length with said striating means in engagement with said material, said last named means comprising a cam carried by said head-elevating means, an operating shaft, means connected to said operating shaft and engageable with said cam for rotating said shaft, and a linkage connected to said head for translating said rotary motion of said operating shaft into a generally diagonal motion of said striating means with respect to its length.
2. In a decorating machine, the combination of a head

mounted on slides for reciprocation in a vertical direction toward and away from a surface to be decorated, striating means carried by said head and engageable with the surface to be decorated when said head is in lowered position, sliding blocks carried by said head slides, mounting blocks on which said head is mounted for sliding movement in a horizontal plane in a direction diagonally of the length of said head on said sliding blocks, a cam for reciprocating said head, and means carried by said cam for imparting diagonal motion to said head in timed relationship with the vertical motion of said head to move said striating means diagonally when the same has been lowered into engagement with the surface to be striated, said last named means comprising operating shafts carried by said head slides, linkages connecting said operating shafts to said head-mounting blocks, and means for imparting coincidental motion of rotation to said operating shafts to move said mounting blocks and the block carried thereby in a diagonal direction with respect to the length of the block.

3. In a decorating machine having a head mounted on a pair of vertically reciprocable head slides for movement toward and away from a surface to be decorated lying in a substantially horizontal plane therebelow and elevating cams having actuating surfaces for vertically reciprocating said head slides with a downward motion, a dwell, and an upward motion, the combination of striating means on said head, slide blocks mounted on said head slides, mounting blocks carried by said head slides and supporting said head for limited sliding motion in a horizontal plane substantially diagonally of the length of said head, operating shafts carried by said head slides, and head-traversing cams carried by said head-elevating cams having actuating surfaces for imparting motion to said operating shafts.

ating shafts to rotate the same in one direction during the dwell interval of said head-elevating cam and to dwell during a portion at least of the head-elevating interval of said head-elevating cam.

- 5 4. In a decorating machine having a head mounted on a pair of vertically reciprocable head slides for movement toward and away from a surface to be decorated lying in a substantially horizontal plane therebelow and elevating cams having actuating surfaces for vertically reciprocating
  - 10 said head slides with a downward motion, a dwell, and an upward motion, the combination of striating means on said head, slide blocks mounted on said head slides, mounting blocks carried by said head slides and supporting said head for limited sliding motion in a horizontal plane substantially diagonally of the length of said head, operating shafts carried by said head slides, head-traversing cams carried by said head-elevating cams having actuating surfaces for imparting motion to said operating shafts to rotate the same in one direction during the
  - 15 dwell interval of said head-elevating cam and to dwell during a portion at least of the head-elevating interval of said head-elevating cam, and spring means for urging said operating shafts to rotate the same in a direction opposite to that imparted by said head-traversing cams
  - 20 to move said head in a horizontal direction to its initial position subsequent to elevation of said striating means away from said surface to be decorated.
  - 25
